WILHELM SCHMIDT, OF CASSEL-WILHELMSHÖHE, GERMANY, ASSIGNOR TO SCHMIDTSCHE HEISSDAMPF GESELLSCHAFT MIT BESCHRÄNKTER HAFTUNG, OF CASSEL, GERMANY, A CORPORATION OF GERMANY.

WATER-TUBE BOILER.

1,072,174.

Specification of Letters Patent.

Patented Sept. 2, 1913.

Application filed April 12, 1911. Serial No. 620,540.

To all whom it may concern:

Be it known that I, WILHELM SCHMIDT, a subject of the King of Prussia, Emperor of Germany, and a resident of Cassel-Wilhelmshöhe, Germany, have invented a new and useful Improvement in Water-Tube Boilers, of which the following is a specification.

My invention relates to water tube boilers and especially to such boilers when provided with means for superheating, or for both superheating and heating the feed water.

The object of my invention is to provide a practical water tube boiler capable of generating highly superheated steam at pressures as high as 60 atm. or more; preferably I employ small diametered water tubes instead of the larger tubes commonly used. At such pressures the boiling point of water is considerably higher than at pressures hitherto employed, being *e. g.* at 60 atm., about 273° C. as compared with 200° C. at 15 atm. Moreover, it must be borne in mind that at high pressure the circulation of the water is considerably less active. Such circulation, as is well known, is brought about chiefly by small bubbles of steam rising during evaporation, but the volume of these small steam bubbles for equal weights of water evaporated, is considerably decreased when high pressures are employed, so that the action of the steam bubbles on the circulation of the water naturally decreases. Thus at a pressure of 60 atm. the circulation of the water is only about half as effective as at a pressure of 15 atm.

The effects of the higher temperature of the mixture of steam and water and the greatly reduced water circulation combine to lower to a dangerous degree the cooling action of the boiler water on the water tubes, and the latter will, therefore, other things being equal, be strained much more severely at the proposed pressures than at those hitherto employed. These dangerous strains are produced when the tube walls are but slightly overheated.

The effect of the high pressures proposed has also to be considered in relation to the superheating of the steam. The requirements, however, in this connection are somewhat different from those associated with the generation of steam, since as remarked above the temperature of saturated steam

at the pressures proposed being very high, the superheating must be carried further than has been usual hitherto, so that it becomes necessary to consider temperatures of 400° C. and more. This, of course, increases the risk of the superheating tubes becoming red hot, a condition which it is essential to avoid in view of the possibility of the tubes bursting under the high pressure. Care must therefore be taken that the flue gases do not come into contact with the superheater tubes in too hot a condition. The employment of such cooled flue gases necessitates however an intense heating of the superheater if it is desired to avoid making the superheater unduly large in proportion to the other elements of the boiler. Finally, it must be remembered that the heating gases in consequence of the high temperature necessitated by the high pressure are still so hot when leaving the superheater that their immediate exhaust or escape into the chimney would be very uneconomical even in marine boiler installations. Some method of utilizing this excess heat becomes desirable therefore, though it is no longer suitable for generating steam owing to the high boiling point.

My invention, which will now be described, provides an arrangement in which the foregoing considerations are given full effect.

Referring to the drawings—Figure 1 illustrates one form of the invention in cross section as applied to a marine boiler; Fig. 2 is a section taken through a detail on the line 2--2 of Fig. 1; and Fig. 3 is a cross section through half of a similar type boiler constructed according to a modification of my invention.

The boiler shown in Figs. 1 and 2, consists of three upper drums, A, A' and A'', and three lower drums, B, B' and B'', these sets of drums being connected with each other by means of the water tubes, C. The lower drums are separated from each other by means of grates, R, R'. The heating flues are formed and bounded by tube walls (shown hatched for greater clearness) D, consisting of water tubes arranged closely together and communicate with the chimney by means of passages, E. The heating flues are so arranged that the current of hot gases passes through them transversely,

i. e., at right angles to the longitudinal direction of the upper and lower drums. Closing or sealing plates, F, are arranged between the upper drums; these plates extend over the whole length (or depth) of the boiler and are provided with apertures G over which are arranged flat slides H which can be moved to and fro by means of an operating rod J. The right hand half of the boiler shown in Fig. 1 will now be described. The heated furnace gases ascending from the grate R' are divided into two currents, one of which passes through the heating flue K and the other through the heating flue L. These flues, K and L, together form the first heating flue of the boiler and contain all the water tubes of the right hand half of the boiler which are used for evaporating purposes. The two currents of heating gas on leaving the flues K and L unite and flow together through the comparatively narrow second heating flue M. The superheater is arranged in the latter flue and consists of a cylindrical vessel, N, divided into two chambers by a longitudinal partition, and of U-shaped pipes O, connecting said two chambers with each other, the pipes, O, extending parallel to the water tubes of the boiler. The shape of the superheater is therefore conformed to the other elements of the boiler while the steam vessel N is arranged in the coldest portion of the heating flue, since it is especially necessary to protect it against high temperatures owing to its size and numerous tube connections. The third heating flue P, accommodates the tubes of the feed water heater; this consists of tubes Q, which connect a compartment S, of the bottom drum, B², with the upper drum A².

The general arrangement of the boiler and the distribution of the heating surface, as above described, is such that the superheater is protected against overheating, not only during normal working conditions but also during forced working and normal heating-up. The higher temperature of the heating gases when adopting forced working is partly balanced by the fact that the steam, in consequence of the larger demand, passes through the superheater tubes, O, at a greater velocity, so that the walls of said tubes are cooled to a greater degree. During normal heating-up, the superheater is not overheated as the comparatively large heating surface provided by the water tubes in front of it extracts a greater amount of heat from the heating gases than during normal working. During forced heating-up, however, the apertures or openings, G, provided in the closing or sealing plates, F, may be opened by means of rod, J, so that cold air can pass from the outside of the boiler through these openings, G, and mix with the heating gases, so that the lat-

ter enter the superheater in a cooled condition.

The left half of the boiler is substantially like the half just described save that the superheater and feed water heater are of somewhat different shape. The superheater instead of being provided with U-shaped pipes is fitted with serpentine pipes, while the feed water heater tubes, Q, are connected at their lower ends to a cylindrical water vessel, T, independent of the lower drum, B.

In the example shown in Fig. 3, the general arrangement of which corresponds to the left hand half of the form shown in Fig. 1, the second heating flue, M, accommodating the superheater is provided with a damper, U, arranged above the superheater. The feed water heater comprises two flues, V and X, of unequal width, the narrower flue, V, being arranged next to the superheater and communicating with the superheater flue at both ends, while it communicates with the flue, X, at its lower end only. The damper, U, is so disposed that in one of its extreme positions it closes the superheater flue, while in its other extreme position it closes the flue, V. With forced heating-up the damper, U, is moved into the position shown in dotted lines, so that the superheater flue, M, is completely closed. In this case the whole of the heating gases passes from the first heating flue directly into the flue, V, and from there into the flue, X. By adjusting the damper in an intermediate position it is possible to regulate the superheating temperature as may be required.

The heating flue, V, may contain no water tubes at all; it is however, advisable to arrange a part of the feed water heater tubes in this flue as shown.

It is of course obvious that in addition to the forms illustrated and described numerous modifications of the invention are possible. For instance, the tube walls, D, separating the two parallel flues in the first heating flue may be omitted entirely. It will be seen, therefore, that according to the present invention, the water tubes serving for generating the steam are mainly arranged in the first heating flue and a superheater and feed water heater are arranged in series in the second and following heating flues. The first heating flue consisting of two parallel flues opening into a common second heating flue, while the tubes of the two parallel flues of the first heating flue start from two lower drums arranged on either side of the furnace, the arrangement being such that the current of hot gases passes through the boiler transversely to the axis of the upper and lower drums.

The arrangement of two heating flues

above the furnace permits the use of a very large number of water tubes so that even with an excessive demand on the boiler only a moderate heating of the first heating flue is necessary. Preferably all the water tubes serving for generating the steam are arranged in the first heating flue and it is advisable in this connection to provide the parallel flues with high inlet openings or 10 to leave them entirely open toward the furnace, so as to reduce as much as possible the harmful formation of pointed flames where the gases enter the parallel flues. In addition, the arrangement whereby the current of heating gases flows in a direction transverse to the longitudinal axis of the upper and lower drums favorably influences a moderate heating, for this arrangement allows the heating gases to enter from any 15 point of the grate directly into the portion of the heating flues arranged above it. The heating gases will, therefore, not crowd together at certain places, as is the case when they flow parallel to the longitudinal axis 20 of the boiler or in other words, when the heating gases enter the heating flues through an opening arranged at the end of the grate. This direction of flow of the heating gases also insures all the water tubes of the heating flues, being heated uniformly, a matter 25 of the greatest importance for the required moderate heating. If the heating gases were allowed to flow parallel to the longitudinal direction of the boiler, then the 30 water tubes situated at the inlet of the heating flues would be subjected to a strain considerably greater than the water tubes situated at the end of the heating flues.

The large heating surface provided in the 35 first heating flue sufficiently insures the heating gases being cooled down to the low temperature desirable for the superheater. On the other hand the contraction (as regards cross sectional area) to which the 40 heating gases of the two parallel flues are subjected when passing through the superheater flues results in a substantial increase in the velocity of the heating gases, so that the heating of the superheater when of moderate dimensions becomes intense. Further 45 the direction of flow of the current of heating gases adopted in accordance with this invention, *i. e.*, transversely to the longitudinal direction of the upper and lower drums 50 is of importance to the superheater as it is solely because of this arrangement that all the superheater tubes are acted upon by equally hot gases. The latter is necessary 55 for insuring a sufficient superheating of the total quantity of steam generated, as at the 60 high pressure of 60 atm. and more, the difference in temperature between the wet steam and the heating gases entering the superheater is relatively speaking small.

65 The heating surface, after the super-

heater, is used for heating the boiler feed water and insures a very efficient utilization of the hot gases.

The invention may also be applied to stationary boilers.

Having now particularly described and ascertained the nature of my said invention and in what manner the same is to be performed, I declare that what I claim is:

1. In a water tube boiler provided with upper and lower drums, and a plurality of heating flues extending in opposite directions arranged in series transversely to the length of the drums the flue nearest the grate being divided into two parallel flues, 75 water tubes substantially all arranged in said parallel flues and a superheater and feed water heater in following flues, as and for the purpose described.

2. In a water tube boiler provided with upper and lower drums, and a plurality of heating flues extending in opposite directions arranged in series transversely to the length of the drums the flue nearest the grate being divided into two parallel flues opening 80 into a single adjacent flue, water tubes substantially all arranged in said parallel flues, a superheater in the adjacent flue and a feed water heater in the following flue, as and for the purpose described.

3. In a water tube boiler provided with upper drums, a lower drum each side of the grate, and a plurality of heating flues extending in opposite directions arranged in series transversely to the length of the drums the flue nearest the grate being divided into two parallel flues, 95 water tubes starting from said lower drum and substantially all arranged in said parallel flues, and a superheater and feed water heater in following flues, as and for the purpose described.

4. In a water tube boiler provided with upper and lower drums and a plurality of heating flues extending in opposite directions arranged in series transversely to the length of the drums the flue nearest the grate being divided into two parallel flues, 100 water tubes arranged in said parallel flues, a regulator at the outlet of said parallel flue for the admission of cold air to the heating gases, and a superheater and a feed water heater in the following flue, as and for the purpose described.

5. In a water tube boiler provided with upper and lower drums and a plurality of heating flues extending in opposite directions arranged in series transversely to the length of the drums, the flue nearest the grate being divided into two parallel flues, 110 water tubes arranged in said parallel flues, a superheater in the adjacent flue, a feed water heater in a following flue and a damper in the superheater flue, said damper serving to divide gases going to said following flue between said superheater flue and

an intermediate flue in any desired proportion, as and for the purpose described.

6. In a water tube boiler provided with upper and lower drums, and a plurality of heating flues extending in opposite directions arranged in series transversely to the length of the drums the flue nearest the grate being divided in two parallel flues opening into a single adjacent flue, water tubes substantially all arranged in said parallel flues and starting from two drums situated one on each side of the grate, a superheater and a feed water heater in series in the adjacent flue and in the following flues, and a damper in the superheater flue, said damper serving to divide gases going to said following flues between said superheater flue and an intermediate flue in any desired proportion, as and for the purpose described.

7. In a water tube boiler provided with upper and lower drums, and a plurality of heating flues extending in opposite directions arranged in series transversely to the length of the drums the flue nearest the

grate being divided in two parallel flues opening into a single adjacent flue, water tubes arranged in said parallel flues and starting from two drums situated one on each side of the grate, a superheater and a feed water heater in series in the adjacent flue and in the following flues, and a damper in the superheater flue, said damper serving to divide gases going to said following flues between said superheater flue and an intermediate flue in any desired proportion, as and for the purpose described.

In testimony whereof, I have hereunto set my hand in the presence of two subscribing witnesses.

WILHELM SCHMIDT.
